UNITED STATES PATENT OFFICE.

HERBERT A. THAYER, OF PROVIDENCE, RHODE ISLAND.

DESIGN FOR A FRAME FOR HOLDING A NUMBER-PLATE AND ANOTHER DESIGNATING DEVICE.

58,839.

Specification for Design.

Patented Aug. 30, 1921.

Application filed May 2, 1921. Serial No. 466,233. Term of patent 7 years.

To all whom it may concern:

Be it known that I, HERBERT A. THAYER, a citizen of the United States, residing at the city of Providence, county of Providence, and State of Rhode Island, have invented a new, original, and ornamental Design for a Frame for Holding a Number-Plate and Another Designating Device, reference being had to the accompanying drawing, forming a part thereof.

Figure 1 is a face view of a frame for

holding a number plate and another designating device, illustrating my new design.

Fig. 2 is an edge view sectioned on line 2—2 of Fig. 1, of a frame for holding a number plate and another designating device, illustrating my new design.

I claim:

The ornamental design for a frame for holding a number plate and another designating device, as shown and described.

HERBERT A. THAYER.
